PORTABLE SPRAYING DEVICE

Clifford J. Griffith, Dimondale, Mich., assignor to
Food Machinery and Chemical Corporation,
San Jose, Calif., a corporation of Delaware

Application August 27, 1953, Serial No. 26,611

Term of patent 14 years

(Cl. D14—3)

To all whom it may concern:

Be it known that I, Clifford J. Griffith, a citizen of the United States and a resident of Dimondale, county of Eaton, State of Michigan, have invented a new, original, and ornamental Design for a Portable Spraying Device, of which the following is a specification, reference being had to the accompanying drawings, forming part thereof.

Fig. 1 is a perspective view of a portable spraying device embodying my new design, the view being taken from the front thereof.

Fig. 2 is a perspective view of the portable

spraying device shown in Fig. 1, the view being taken from the rear thereof.

The dominant feature of my design resides in the portion shown in full lines.

I claim:

The ornamental design for a portable spraying device, as shown and described.
